Specification for Design.

Patented Nov. 24, 1914.

Application filed July 27, 1914. Serial No. 853,498. Term of patent 7 years.

To all whom it may concern:

Be it known that I, ANNIE R. PEARCE, a citizen of the United States, and a resident of Providence, in the county of Providence and State of Rhode Island, am the administratrix of the estate of ALDRIDGE G. PEARCE, deceased, who was the inventor of the new, original, and ornamental Design for a Clip for Pens, Pencils, or Similar Articles, of which the following is a specification, reference being had to the accompanying drawing, forming part thereof.

Figure 1 of the drawings is a front elevation of the clip. Fig. 2— is a side elevation

of the clip showing a pen or pencil in dotted lines. Fig. 3— is a top view of the clip showing the ear portions as bent back to encircle the pen or pencil.

I claim:

The ornamental design for a clip for pens, pencils, or similar articles, substantially as shown.

ANNIE R. PEARCE,
Administratrix of estate of Aldridge G. Pearce.
